APPARATUS FOR COVERING RAYON
PACKAGESAdrian J. L. Moritz, Enka, N. C., assignor to
American Enka Corporation, Enka, N. C., a corporation of Delaware

Application June 5, 1944, Serial No. 538,841

1 Claim. (Cl. 226—56)

1

The present invention relates to a method and apparatus for use in the manufacture of rayon and more particularly to a method of covering freshly spun rayon cakes and an apparatus adapted for such use.

In the production of rayon according to the centrifugal process, the thread is collected in a rapidly rotating bucket or pot. During the spinning operation the convolutions of thread are laid up in the bucket to form a relatively hard self-supporting package known in the art as a cake. When the spinning operation has continued for a period of time sufficient to build up a cake of the desired thickness the cake is removed from the bucket and the thread is subjected to the usual after-treating operations in the original cake form. In view of the fact that the thread in freshly spun cakes is subject to damage from handling during the after-treating operations it has become the custom to cover the cakes with elastic socks or sleeves which are sufficiently porous to permit the permeation of the after-treating liquids therethrough but nevertheless constitute a sufficient covering to protect the threads during normal handling.

The past practice has involved the manual application of the socks or sleeves to respective rayon cakes. In the normal application of the sleeves special apparatus has not been employed and the covering of the cakes by hand is very tedious and is, of course, relatively slow. In fact, the manual application of the sleeves to the cakes tends to inhibit the efficiency of the overall treatment to which the cakes are subjected. Although the manual application of the sleeves may not appear upon casual observation to involve a substantial loss of time, actually it is well known to those skilled in the art that in rayon plants in which thousands of cakes are after-treated daily the manual application of the sleeves to the individual cakes involves a tremendous loss of time.

The present invention has as an object the application of socks or sleeves to cakes of thread in a manner by which the above-referred to disadvantages are overcome.

A further object of the present invention is the provision of an apparatus which materially reduces and in some forms substantially eliminates the manual manipulation of the sleeves in the application thereof to the thread cakes.

This invention further contemplates the provision of a method for covering cakes of rayon and the like in an orderly manner and the effecting of a relatively tight fit between the covering sleeves and the respective cakes without the dis-

2

placement of layers of the thread in the cake or injuring the thread.

An additional object of the present invention is the provision of a method of, and apparatus for, the application of sleeves to rayon cakes without incurring tangling of portions of the sleeves or effecting wrinkling thereof.

Other objects and advantages of the present invention will be apparent from the following detailed description when considered in connection with the accompanying drawings, wherein

Figure 1 is a sectional view of a normal rayon cake as formed in a centrifugal bucket machine;

Figure 2 is an elevational view of one form of apparatus constructed in accordance with the present invention with a part being broken away to illustrate the elements thereof in section;

Figure 3 illustrates the apparatus shown in Figure 2 with a sleeve positioned thereover with the upper end folded in a manner to permit the placing of a cake thereover;

Figure 4 is a view of the apparatus illustrated in Figure 2 with the cake and supporting means partially depressed to show the manner in which the lower end of the sleeve is gradually applied upwardly along the outer surface of a cake;

Figure 5 is a view similar to Figure 4 in which the cake and supporting mechanism have been completely depressed whereby the lower end of the sleeve has been completely applied to the outer wall of the cake, the sleeve as illustrated having been unfolded at the upper end and spread outwardly to permit it to be drawn over the upper edge of the cake and downwardly over the side wall thereof;

Figure 6 illustrates a cake completely covered with a sleeve, the top part of which is shown overlapping the bottom part along the outer wall of the cake;

Figure 7 is a view of a modified form of apparatus constructed in accordance with the present invention;

Figure 8 is a view in partial elevation illustrating another modified form of apparatus constructed in accordance with the present invention;

Figure 9 is a top plan view of the apparatus shown in Figure 8;

Figure 10 illustrates a sleeve positioned over the modified form of apparatus shown in Figure 8 with an end of the sleeve folded over in position so that the apparatus is adapted to receive the cake for the application of the sleeve thereto;

Figure 11 is a view similar to Figure 10 in which a cake has been inserted into the apparatus and

the sleeve applied to the lower portion thereof; and

Figure 12 is a view similar to Figure 11 in which the folded end of the sleeve has been forced outwardly by a series of expanding fingers and spread over the upper edge of the cake and the upper portion of the outer wall thereof by the upward movement of the cake support after the fingers have been expanded.

In referring to the drawings in detail and more particularly to Figures 1-6, inclusive, the numeral 10 designates a cylindrical pan or cup-shaped member, the circumference of which is slightly larger than the circumference of the rayon cakes 11 to be handled by the apparatus. Arranged concentrically of pan 10 and adapted to be reciprocated therethrough is a pedestal 12 provided with a knob 13 at the upper end thereof. Pedestal 12 has its lower end 14 of reduced diameter, which portion 14 is adapted to be received in and be guided by a cylinder 15 extending from a base 16 upon which the pan 10 is supported. A disc 17 provided with a central opening 18 is fitted over the reduced portion 14 of pedestal 12 and is resiliently maintained against shoulder 19 formed on pedestal 12 as a result of the reduced diameter of the lower portion thereof. Disc 17, while being of an area to substantially fill the cross-section of pan 10, has sufficient clearance between it and the wall of pan 10 to permit its free movement within the pan. A coil spring 20 engaging the bottom of the disc 17 encircles portion 14 of the pedestal. Spring 20 is supported by bottom 21 of pan 10 and thereby provides resilient support for disc 17 and pedestal 12. Mounted radially in base 16 is a spring latch member 22 having a handle 23 and a notch-engaging bar 24. Bar 24 is normally urged to bear against portion 14 of pedestal 12 and a groove 25 is formed in portion 14 of the pedestal whereby when the pedestal is depressed to a position where the groove is opposite bar 24 the bar will be forced into the groove and will retain the pedestal in a depressed condition until the latch is withdrawn by the handle 23. When the latch is withdrawn and no pressure is placed upon the knob 13 of pedestal 12, spring 20 will cause the pedestal and disc 17 to be elevated to the position shown in Figure 2.

A sock or sleeve 26 is illustrated in Figures 2-6, inclusive, the sleeve being shown in the various positions it assumes during the application of the sleeve to the cake as the apparatus is operated. The application of a sleeve to a cake with the use of the apparatus shown in Figures 2-5, inclusive, may be readily understood by reference to the figures. In Figure 3 the sleeve 26 is shown as having its lower end drawn over pan 10 and its upper end folded over knob 13. The configuration of knob 13 may be modified in various ways, such as, providing a cup shaped or hollow upper portion to hold the sleeve 26 in folded condition. In this position a cake 11 may be readily placed over the pedestal whereupon the sleeve assumes the position shown in Figure 2. Upon forcing the pedestal downwardly from the position shown in Figure 2 the extending portion of the sleeve which originally was caused to overlie the outer wall of the pan 10 is drawn upwardly over the upper edge of the pan and is applied evenly and with uniform tension to the lower portion of the outer wall of the cake. As this operation is continued and the pedestal, together with the disc 17 is depressed to the position illustrated in Figure 5, the lower end of the sleeve is then completely applied to the outer lower portion of the cake and the

inner wall of the cake. When the pedestal has reached the position illustrated in Figure 5, bar 24 of latch 22 enters groove 25 of portion 14 of the pedestal, and the elements are maintained in the position illustrated; whereupon the operator may spread the folded portion of sleeve 26 outwardly and downwardly over the upper portion of the cake to a position where the ends of the sleeve overlap. When the operation has reached this stage latch bar 24 is withdrawn by means of handle 23 and spring 20 causes the pedestal and disc 17, together with the cake and sleeve applied thereto, to be moved upwardly to the position illustrated in Figure 2, whereupon the cake in the form illustrated in Figure 6 is removed and ready for the after-treating operations.

Although the apparatus shown in Figures 2-6, inclusive, inherently avoids the creation of relative sliding action between the sleeve and the cake, a simplified device such as that shown in Figure 7 may be used if the cake and sleeve are manipulated with sufficient care to avoid injuring the thread in the cake. The modified form of apparatus illustrated in Figure 7 includes a pan 27 and a rigid pedestal 28 mounted concentrically of the pan 27 and anchored in base 29 by means of screw threads 30. Pedestal 28 is provided with a knob 31.

In utilizing the simplified form of device illustrated in Figure 7, a sleeve 26 is drawn over the pan 27 in a manner similar to that illustrated in Figure 3 and the upper portion of the sleeve is folded upon knob 31. The cake 11 is then placed over pedestal 28 whereupon it engages sleeve 26 and as the cake is inserted into pan 27 the lower portion of the sleeve is drawn over the upper edge of pan 27 and the sleeve is applied to the outer surface of the cake in the manner heretofore described with respect to the preferred form of the invention. If the folded upper portion of the sleeve is permitted to unfold and move downwardly with the cake, relative sliding action between the cake and sleeve will be eliminated. After the cake has been fully inserted within the pan 27 the upper portion of the sleeve may be spread outwardly over the upper portion of the cake and if desired it may be spread downwardly over the wall of pan 27 whereupon the cake may be withdrawn and the sleeve will assume the position upon the cake illustrated in Figure 6. If desired, when spreading the upper portion of the sleeve upon the cake in carrying out the method with the device shown in Figure 7, the cake may be partially removed from the pan before the sleeve is spread thereover.

The modified form of apparatus, illustrated in Figures 8-12 inclusive, is formed with a cup-shaped member or pan 32 mounted upon a base 33. The base 33 functions as a bottom for the pan 32 and is supported over a circular opening in a platform or table 34. The circular opening is about the same size as the circumference of the pan 32. The base 33 is provided with a series of radial slots 35 adapted to guide respective arms 36 in their movement to and from the center of the pan.

Arms 36 are adapted to be moved in unison to and from the center of the pan by suitable means arranged below base 33. The arms 36 may, for instance, be caused to expand outwardly by means of a mechanism such as that shown in U.S. Patent No. 2,213,366 to Peter P. Kriek. Each of the arms is provided with extensions 37 at their upper ends which are bent outwardly and then

downwardly to form fingers 38. Since the arms 36 are supported from a point below the base 33 and are fixed against vertical movement, the slots 35 in the bottom of the pan act as guide-ways for the arms but the pan and base may nevertheless be reciprocated toward and away from extensions 37 when desired. In order to effect the elevation and depression of the pan 32 and base 33, a yoke 39 is fixed to the bottom of base 33 and a shaft 40 on which a collar 41 is mounted, is passed through the yoke and extends through the base. The lower end of shaft 40 is connected to the telescoping member of the mechanism disclosed in the said Kriek patent, which telescoping member also acts to expand arms 36. When the arms have been fully expanded, the collar 41 will contact the yoke 39 as a result of the upward motion of shaft 40, and upon further upward movement of shaft 40, the pan 32 and base 33 will be raised as shown in Figure 12.

In applying a sock or sleeve to a cake with the use of the apparatus illustrated in Figures 8-12 inclusive, an end and intermediate portion of the sleeve is drawn over the outer surface of pan 32 and the upper end of the sleeve is folded over extensions 37 of arms 36. A cake is then placed over the arms 36 and inserted into the pan 32 in the same manner as the cake is inserted in the pan 27 of the apparatus illustrated in Figure 7. As the cake is passed downwardly into the pan 32 the extending end of the sleeve is drawn upwardly over the edge of the pan and is applied to the outer surface of the cake. At this stage in the operation the mechanism for expanding the arms 36 is put into operation and the arms together with the extensions are forced outwardly and resultantly spread the upper previously folded portion of the sleeve to a position overlying the upper edge of the cake. The collar then contacts the yoke which effects the elevation of pan 32 whereby the cake and the pan are raised into position within the downwardly extending fingers 38 to the position shown in Figure 12. The sleeve is then straightened to avoid wrinkles, the pan is lowered and the arms are retracted to their original position whereupon the cake may be readily removed from the apparatus with the protecting sleeve thereon as illustrated in Figure 6.

Various modifications may be made herein without departing from the spirit and scope of the invention, and the invention is to be limited only to the extent of the appended claim.

5 What is claimed is:

An apparatus for covering a rayon cake with a tubular sleeve which comprises a stationary pan provided with a flat bottom and a cylindrical side wall having a circumference slightly greater than a cake of rayon, said side-wall being free of obstructions to thereby receive a tubular sleeve thereover and a rayon cake therein, a base member for supporting the pan, a rigid pedestal fixedly mounted concentrically of the pan and anchored in the base member, said pedestal extending vertically a distance greater than the height of said wall, means on the upper end of the pedestal for loosely retaining one end of the sleeve in a gathered condition whereby when the other end of the sleeve is expanded over the wall of the pan and a cake is deposited over the pedestal retaining the gathered portion and inserted in the pan, the expanded portion of the sleeve is caused to cover a substantial part of the outer surface of the cake and the gathered end is simultaneously permitted to unfold and move downwardly whereupon the remainder of the cake surface can be covered by spreading the upper portion outwardly over the wall of the pan.
